UNITED STATES PATENT OFFICE.

LOUIS GOLDSMITH, OF NEW YORK, N. Y.

TRUNK.

SPECIFICATION forming part of Letters Patent No. 636,794, dated November 14, 1899.

Application filed August 28, 1899. Serial No. 728,666. (No model.)

To all whom it may concern:

Be it known that I, LOUIS GOLDSMITH, a citizen of the United States, residing at New York, in the county and State of New York, 5 have invented certain new and useful Improvements in Trunks, of which the following is a full, clear, and exact description.

My invention relates to trunks and the like, and particularly to a trunk designed to carry to a number of ladies' skirts and other garments, so that the same may be packed and transported without injury to the form of the garment by reason of unnecessary crushing of the folds thereof.

15 While the trunk is principally designed to carry ladies' wearing-apparel, it is also useful to carry men's wearing-apparel.

In the drawings, Figure 1 is a view of an open trunk of my improved construction. 20 Fig. 2 is a section on the line 2 2 of Fig. 1 looking in the direction of the arrow. Fig. 3 is a plan view of a detail.

A is the body of a trunk. B is a suitable cover therefor, which may be hinged or otherwise attached thereto.

25 C are guideways which may be undercut or otherwise suitably shaped to receive the slide-rods D, any number of which may be employed. Upon these slide-rods D may be 30 carried hooks E E or other suitable supporting devices—such as, for example, a screw-eye F.

G is a hook which may support a coat or waist supporting frame H.

35 I is a rack secured near the bottom of the trunk in any desired manner and supporting forwardly-projecting spring-bars J J, arranged in sets of preferably two in each set. These spring-bars J J normally tend to bear

40 against each other and may be supplemented by a fastening-loop K, if desired. The rack I and spring-bars J are preferably located near the end of the trunk opposite the slide-bars and hangers D.

45 L represents a lady's skirt, and M a lady's waist.

Operation: The trunk is opened and placed upon one end—for example, as shown in Fig.

1. One of the slide-bars D may be then re- 50 moved and a skirt, as L, may be attached thereto at the points E E by flexible loops, such as are commonly attached to ladies'

skirts. If it is desired to pack a waist, such as H, the same may be placed over the supporting-frame H in the manner shown in Fig. 55 2. The slide-bar D may then be reinserted into place in the trunk, as shown, while the bottom of the skirt may be inserted between the spring-bars J J, which may be brought together and fastened. Any suitable number of skirts and waists may be thus packed compactly and neatly without unnecessarily wrinkling or otherwise injuring the hang of the garment.

Obviously the bars J J need not be spring-bars, since the same end would be effected if they were simply brought together and fastened by such a means as a loop K after the garment has been put in place.

If desired, another rack, as I, may be provided midway in the length of the trunk, so as to provide a supplemental clasp for the garments at an intermediate point in the length, and such an addition is too obvious to require a detailed illustration.

75 The trunk should properly be constructed of a length slightly greater than the ordinary or average skirt, so that folding will be unnecessary. This is not, however, a requirement, since I have found that in practice the 80 garment will not become wrinkled if it is turned slightly at the bottom, so as to rest upon the end of the trunk when in the position indicated in Figs. 1 and 2, the bottom of the trunk in these figures being in reality the 85 end of the trunk under normal conditions. When a trunk of this character arrives at its destination, it is ordinarily placed upon one end, which serves as the bottom, so that the 90 contents will remain in an upright position.

What I claim is—

1. In a trunk a plurality of independent slide-bars at one end thereof, means for supporting a garment carried by each of said slide-bars, a plurality of independent sets of non-removable clamping-bars in said trunk toward the opposite end thereof and means to press the clamping-bars of each independent set into engagement with a garment embraced thereby.

2. In a trunk a plurality of independent slide-bars at one end thereof, means for supporting a garment carried by each of said slide-bars, a plurality of independent sets of non-

removable spring clamping-bars in said trunk toward the opposite end thereof, each of said bars being mounted near its extremity, and means to press the clamping-bars of each independent set into engagement with a garment embraced thereby.

3. In a trunk a plurality of independent slide-bars at one end thereof, means for supporting a garment carried by each of said slide-bars, a plurality of independent sets of non-removable clamping-bars in said trunk to-

ward the opposite end thereof, each of said bars being mounted near its extremity and a loop to hold the clamping-bars of each independent set into engagement with a garment 15 embraced thereby.

Signed at New York, N. Y., this 25th day of August, 1899.

L. GOLDSMITH.
